UNITED STATES PATENT OFFICE.

ERNST KOERTING, OF PEGLI, ITALY, ASSIGNOR TO SCHUTTE & KOERTING COMPANY
OF PHILADELPHIA, PENNSYLVANIA, A CORPORATION OF PENNSYLVANIA.

INJECTOR.

1,111,542.

Specification of Letters Patent. Patented Sept. 22, 1914.

Application filed February 19, 1914. Serial No. 819,608.

To all whom it may concern:

Be it known that I, ERNST KOERTING, a subject of the Emperor of Germany, residing at Pegli, in the Province of Liguria, in 5 the Kingdom of Italy, have invented certain new and useful Improvements in Injectors, of which the following is a true and exact description, reference being had to the accompanying drawings, which form a part 10 thereof.

My invention relates to boiler feed injectors and has for its object to provide a device especially adapted for economically feeding hot water to a boiler.

15 Broadly speaking my invention consists in combining with an injector proper, preferably a two tube injector, a steam jet pump and a feed water heater situated between said pump and the injector so that the feed 20 water is raised in pressure by the jet pump, then heated in the feed water heater and then fed through the injector to the boiler.

A special feature of my invention consists in the construction of a special casing 25 adapted to contain the jet pump and injector and to be combined with them and a feed water heater as described.

The nature of my invention will be best 30 understood as described in connection with the drawing, which is a sectional elevation showing the casing, the jet pump and injectors and their connection with a feed water heater and in which—

35 A is the casing having a steam inlet B leading to a chamber B', from which lead the steam jets C, C' and C'', controlled by valves D, D' and D'' which are actuated by a hand lever D³, acting through rod D³ and cross bar D⁴.

40 E is a port for feed water leading to a chamber E' in which is situated the combining tube of a jet pump F set to receive steam from nozzle C and having its delivery tube opening into a chamber G from which 45 a conduit H leads to a feed water heater which, as shown, is a casing I, having a head I' to receive the steam connecting with a similar head (not shown) by tubes I², the lower, unshown, head having also connected 50 to it the return tubes I⁶ leading to an annular header chamber I⁶, which connects through a conduit H' with the chamber G' in the casing A. The body I⁷ of the heater I is filled with exhaust steam and the heater 55 indicated is of the surface condenser type.

The chamber G' delivers the feed water at the increased pressure imparted by the jet pump and increased temperature imparted by the feed water heater to the injector tube F' which delivers it with increased pressure 60 to chamber J whence it passes through injector tube F² to chamber K and thence through port L and valve M to the boiler.

N is a valve chamber connecting as shown with chambers G, J and K, through posts O, 65 O' and O'' and with chamber N' from which port N² leads to the atmosphere.

P is a valve stem connected to valve P', carrying valve P² at its lower end and chambered so as to progressively close the ports 70 as the valve is moved. Usually the valve P' is controlled from the lever D⁵ as through eccentric Q, rods Q', eccentric Q² and yoke Q³ connecting it to rod P. The overflow valve, starting lever and connections are all 75 of familiar types and are not therefore fully illustrated or described.

It is of course well known that a boiler 80 injector will not under ordinary conditions feed water even approaching a temperature of 212° F. With the combination of the jet pump and feed water heater to raise the pressure and temperature of the water fed to the injector tubes proper the injector can be made to successfully feed water of 212° F. 85 to a boiler and the water can be raised to this temperature without an excessive use of live steam and hence with economy.

Having now described my invention, what I claim as new and desire to secure by Letters Patent is,

1. A boiler feeding device for feeding hot water consisting of an injector in combination with a steam jet pump and a feed water heater connected to receive water from the 95 jet pump and supply it to the injector.

2. A boiler feeding device for feeding hot water consisting of a two tube injector in combination with a steam jet pump and a feed water heater connected to receive water from the jet pump and supply it to the injector. 100

3. A boiler feeding device for feeding hot water consisting of a casing having separate chambers for a steam injector and for a 105 steam jet pump with separate feed water and delivery ports for each in combination with an injector and a steam jet pump situated in said casing and means for forcing steam into the injector and pump. 110

4. A boiler feeding device for feeding hot water consisting of a casing having separate chambers for a steam injector and for a steam jet pump with separate feed water and delivery ports for each, in combination with a two tube injector and a steam jet pump situated in said casing and means for forcing steam into the injector and pump tubes.
- 10 5. A boiler feeding device for feeding hot water consisting of a casing having separate chambers for a steam injector and for a

steam jet pump with separate feed water and delivery ports for each, in combination with an injector and a steam jet pump situated in said casing, a feed water heater connected to the delivery port of the jet pump and to the feed water port of the injector and means for forcing steam into the injector and pump. 15
